UNITED STATES PATENT OFFICE.

PAUL MATHEWSON, OF NEW YORK, N. Y.

PROCESS FOR MAKING FOOT MOLDS.

Application filed September 12, 1925. Serial No. 56,002.

It is well known that a great many people have more or less trouble with their feet, due to the great difficulty of obtaining properly fitting arch supports or shoes. This difficulty is especially true where the arch supports or shoes are ordered by mail even with the elaborate systems of foot measurement now available.

My invention is intended to overcome this difficulty and enable people to obtain arch supports or shoes which will properly fit their feet, by making a mold of the foot, said mold comprising a somewhat elastic flexible lining, such as the foot portion of a stocking, and a hardened coating thereon, such, for instance, as a wax composition coating; which mold with the lining as a part thereof is so cut along the instep that it can be readily removed from the shoe last on which it is made and also from the foot to which it is shaped, and safely shipped or taken from and to the arch support or shoe manufacturer or dealer, said mold also being provided with means for drawing the mold snugly around the instep of the foot when the mold has been softened, to procure a proper mold of the foot as the coating hardens.

In the accompanying drawings;

Fig. 1 represents the completed mold in perspective.

Fig. 2 represents a longitudinal section showing the method of making the mold on a shoe last.

Fig. 3 represents a transverse section taken in the plane of the line III—III of Fig. 2.

In making the foot mold the shoe last 1 is covered by a somewhat elastic flexible lining, such, for instance, as the foot portion 2 of a stocking, which stocking foot is then coated with a hardening material denoted by 3, which hardening material may be a wax composition which is applied in liquid form and hardens very quickly. This hardening material impregnates and attaches itself to the flexible lining, forming together therewith a mold which closely conforms to the contour of the shoe last. The hardening material which I have found suitable is a composition of paraffin, beeswax, canauba wax and rosin, which composition I find stands up particularly well in shipping the molds in very hot weather.

While the mold is on the shoe last it is cut longitudinally along the instep, as shown at 4, to permit it to be removed from the shoe

last and also from the foot after it has been shaped thereto.

In practice; when it is desired to shape the mold to the wearer's foot, the mold is softened, as, for instance, by hot water, sufficiently to enable the mold to be placed upon the foot. The mold is then drawn snugly around the instep of the foot by suitable devices. In the present instance I have shown the flexible lining as being provided with a series of straps 5 permanently attached to the flexible lining along one side of the cut 4, and a corresponding series of buckles 6 permanently attached to the flexible lining 70 along the other side of the cut.

The mold is then allowed to shape itself to the foot and harden thereon with pressure, applied to the foot, as, for instance, by standing on the foot. After the mold is 75 sufficiently hard, the fastening devices 5, 6 are released to permit the mold to be removed from the foot. The mold may then be shipped or taken to the arch support or shoe manufacturer or dealer so that it may be used as a pattern for selecting a properly fitting arch support or shoe.

What I claim is:—

1. The method of making a foot mold to be used as a pattern for the selection of a properly fitting arch support or shoe, which includes the following steps, placing a flexible lining on a shoe last, coating the lining with a hardening material, allowing the mold to harden, cutting the mold longitudinally along the instep and removing it from the last, softening the mold, placing the softened mold on the foot, allowing the mold to harden and removing the foot shaped mold from the foot.

2. The method of making a foot mold to be used as a pattern for the selection of a properly fitting arch support or shoe, which includes the following steps, placing a flexible lining on a shoe last, coating the lining with a wax composition, allowing the mold to harden, cutting the mold longitudinally along the instep and removing it from the last, softening the mold, placing the softened mold on the foot, allowing the mold to harden and removing the foot shaped mold from the foot.

3. The method of making a foot mold to be used as a pattern for the selection of a properly fitting arch support or shoe, which includes the following steps, placing a flexible lining on a shoe last, coating the lining

with a hardening material, allowing the mold to harden, cutting the mold longitudinally along the instep and removing it from the last, softening the mold, placing the softened mold on the foot, drawing the mold snugly around the instep of the foot by suitable devices, allowing the mold to harden, releasing said devices and removing the mold from the foot.

10 4. The method of making a foot mold to be used as a pattern for the selection of a properly fitting arch support or shoe, which includes the following steps, placing a flexible lining on a shoe last, coating the lining with a wax composition, allowing the mold to harden, cutting the mold longitudinally along the instep and removing it from the last, softening the mold, placing the softened mold on the foot, drawing the mold snugly around the instep of the foot by suitable devices, allowing the mold to harden, releasing said devices and removing the mold from the foot.

15 5. The method of making a foot mold to be used as a pattern for the selection of a properly fitting arch support or shoe, which includes the following steps, placing a flexible lining on a shoe last, coating the lining

with a hardening material, allowing the mold to harden, cutting the mold longitudinally along the instep and removing it from the last, softening the mold, placing the softened mold on the foot, drawing the mold snugly around the instep of the foot by suitable devices, allowing the mold to harden with pressure applied to the foot, releasing said devices and removing the mold from the foot.

20 6. The method of making a foot mold to be used as a pattern for the selection of a properly fitting arch support or shoe, which includes the following steps, placing a flexible lining on a shoe last, coating the lining with a wax composition, allowing the mold to harden, cutting the mold longitudinally along the instep and removing it from the last, softening the mold, placing the softened mold on the foot, drawing the mold snugly around the instep of the foot by suitable devices, allowing the mold to harden with pressure applied to the foot, releasing said devices and removing the mold from the foot.

In testimony, that I claim the foregoing as my invention, I have signed my name this 11th day of September, 1925.

PAUL MATHEWSON.
